UNITED STATES PATENT OFFICE.

BENJAMIN F. CURRY, OF POMONA, CALIFORNIA.

ADJUSTABLE SQUARE AND BEVEL.

1,366,878.

Specification of Letters Patent. Patented Jan. 25, 1921.

Application filed October 13, 1919. Serial No. 330,185.

To all whom it may concern:

Be it known that I, BENJAMIN F. CURRY, a citizen of the United States, residing at Pomona, in the county of Los Angeles and State of California, have invented certain new and useful Improvements in Adjustable Squares and Bevels; and I do declare the following to be a full, clear, and exact description of the invention, such as will enable others skilled in the art to which it appertains to make and use the same.

This invention relates to adjustable angle measuring tools, and more particularly to an improved adjustable square and bevel.

One object of this invention is to provide an improved device of this character which has broad working faces or planes which are adjustable to any desired angle with relation to one another so that the tool is especially useful in connection with a miter box so as to enable the user to quickly and easily lay out and saw or cut a strip of molding at any angle desired.

A further object is to provide an improved tool of this character which is exceedingly strong, rigid, durable, convenient and accurate, and which may be manufactured at a comparatively low cost.

Other objects and advantages may become apparent to persons who read the following details of description in connection with the accompanying drawings in which:

Figure 1 is a top plan view of my improved tool in connection with a miter box.

Fig. 2 is a top plan view of the device showing the same in another relation to the miter box for laying out a different angle without changing the angle of the miter box or of the angle measuring tool.

Fig. 3 shows the device in closed position.

Fig. 4 is a sectional view along the line 4-4 of Fig. 1.

Fig. 5 is a sectional view along the line 5-5 of Fig. 4.

Fig. 6 is a sectional view along the line 6-6 of Fig. 5.

Fig. 7 is a perspective view illustrating one of the main bars which are pivotally connected together to produce the different angles.

Fig. 8 is a top plan view illustrating the device somewhat modified by the use of an attachment or the exchange of links.

Referring to these drawings in detail, in which similar reference characters corre-

spond with similar parts throughout the several views, and in which the numeral 1 indicates an ordinary miter box while the numeral 2 indicates a strip in the position 60 in which its end has been sawed or cut to the desired angle,—

The improved measuring tool comprises a bar 3, a bar 4 pivoted to the bar 3 at 5, a link 6, a second link 7 which has one 65 end interlapped with the link 6 as indicated at 8 in Fig. 6, and adjusting screws or thumb-screws 9, one of these screws being in threaded engagement with the end of the link 6 which interlaps with the link 7, this screw extending through the contiguous end of the link 7, but not being in threaded engagement therewith, so that this screw serves as a pivot which connects the links 6 and 7 to one another and to the 75 bar 3. This thumb-screw 9 also extends through a slot 10 which extends through one of the two walls between which a channel is formed in the side opposite to the working face 11, it being understood that 80 each of the bars 3 and 4 is thus formed with a channel on one side and a working face 11 on the opposite side. The ends of the links 6 and 7 extend into these channels, so that the heads of the screws 9 bind against 85 the outer surfaces of the channel walls and secure the links 6 and 7 in different adjusted positions. In this connection it should be understood that while one of the screws 9 is adjustable along a slot 10, the 90 other screw is adjustable along a slot 12 of the bar 4. One end of the bar 6 is secured by a fixed pivot or screw 13 to this bar 4. From the foregoing description, it will be seen that the device is susceptible 95 of an infinite number of very accurate adjustments. However, the range of adjustment is somewhat limited, as this particular form of the device is intended principally for use in connection with miter boxes 100 and its range is not required to be great because it is intended for use as a complementary device in connection with the 45 degree angle of the miter box, although, it may be used in connection with the other 105 angles of the miter box. In this connection attention might be directed to the fact that ordinary known adjustable miter boxes are usually limited to a few angles most generally in use, such as 45 degrees, 60 110 degrees, etc., and therefore, if the strip 2 is placed parallel with the sides of the miter

box at the 45 degree cutting plane, the strip would be cut at 45 degrees. However, by placing the strip at an angle of 15 degrees to the side of the miter box, in the position illustrated in Fig. 1, the angle 2^a would be 30 degrees with relation to the long edge of the strip 2, because 15 from 45 equals 30. On the other hand, if the strip 2 is placed in the miter box as indicated in Fig. 10 2, and sawed or cut at the 45 degree plane of the miter box, the 15 degrees is added to the 45 degrees so that the angle 2^b is 60 degrees to the long edge of the strip 2. Obviously, by adjusting the device to different angles the angles 2^a and 2^b will be 15 changed accordingly.

In order that this device may be useful as a square and may also be used to lay out angles greater than 45 degrees, an attachment 20 is provided for use in lieu of the links 6 and 7. This attachment is illustrated at 14 in Fig. 8, the same being a link which is longer than the links 6 and 7. By removing the links 6 and 7 and attaching the link 14 25 to the thumb-screws 9 and 13, as shown in full lines in Fig. 8, then opening the device until the thumb-screw 9 reaches the end of the slot 10 nearest the pivot 5, this stops the device in the position for forming a 30 right angle or square. By attaching the pivot or screw 13 to the bar 4 through an aperture 4^a and pivotally connecting the link 14 thereto, as shown in full lines in Fig. 8, the bar 4 may be swung into alignment with 35 the bar 3 (as illustrated in dotted lines) or to any intermediate position.

Although I have described this embodiment of my invention very specifically, it is not intended to limit the invention to these 40 exact details of construction and arrangement, but changes may be made within the scope of the inventive ideas as implied and claimed.

What I claim as my invention is:

45 1. A combination square and bevel comprising arms pivotally connected, links pivotally connected with each other and

slidably connected with one of said bars, one of the links being pivotally connected with the second bar and the second link pivotally 50 and slidably connected with the second bar.

2. The combination of a bar having a slot extending therealong, a second bar having one end pivotally connected to the first bar and having a slot extending therealong, 55 a thumb-screw extending through the slot of the first bar, a pair of links, each link having one end interlapped with one end of the other link and pivotally connected together by said thumb screw, one of said links being pivotally secured to the second bar, and a screw extending through the slot of said second bar and engaged with the other link of said pair, said screws being effective to secure said links in different 60 adjustments along said slots and thereby secure said bars at different angles.

3. In an adjustable tool of the character described, a pair of bars hinged to one another and each having a plane broad 70 working surface and a channel extending therealong on the side opposite to said working surface, one of said bars having a wall of the channel formed with a longitudinally extending slot, a link having one end in the 75 channel of the longitudinally slotted bar, a thumb screw threaded in said end of the link and having a head to engage with the slotted wall for securing this end of the link in different adjusted positions, the other 80 end of the link extending into the channel of the other bar and being pivotally connected to this bar, a second link, and a second thumb-screw, said second link having one end interlapped with the first said link and 85 pivotally secured thereto by the first said thumb-screw, the other end of the said second link being adjustably secured to the bar which is pivotally connected to the bar having said longitudinally extending slot 90 therein.

In testimony whereof I have hereunto set my hand.

BENJAMIN F. CURRY.
